FRANK A. WHITTEN, OF DETROIT, MICHIGAN, ASSIGNOR TO AMERICAN CAR AND FOUNDRY MOTORS COMPANY, OF NEW YORK, N. Y., A CORPORATION OF DELAWARE.

VALVE-OPERATING MECHANISM.

Application filed April 1, 1927. Serial No. 180,184.

Reference is had to the accompanying drawings, which illustrate the preferred form of the invention, though it is to be understood that the invention is not limited to the exact 5 details of construction shown and described, as it is obvious that various modifications thereof within the scope of the claims will occur to persons skilled in the art.

In said drawings:

10 Figure 1 is a longitudinal sectional view, taken on line 1—1 of Fig. 2, with parts broken away;

15 Fig. 2 is a fragmentary top plan view of my improved exhaust heater valve operating mechanism and having parts broken away;

Fig. 3 is a fragmentary top plan view illustrating a crank handle associated with the valve operating mechanism; and

20 Fig. 4 is a horizontal sectional view, taken on line 4—4 of Fig. 1.

My invention relates to exhaust heater valves, and has particular reference to an operating mechanism therefor.

The invention has for its principal object 25 the provision of an exhaust heater valve operating mechanism, wherein a plurality of valves are actuated either to open or closed position simultaneously, and are so arranged as to compensate for one valve moving in 30 advance of another and thereby cause all of them to move in synchronism.

A further object of the invention is to provide a valve mechanism of this character which is compact, simple in construction, and 35 which is free from vibration even though the valves are in a partly open position.

Referring to the invention in detail, the numerals 5 and 6 designate a pair of internal combustion engine exhaust pipes for communication with mufflers 7 by means of casings 8. Supported transversely on each of these casings 8 and communicating therewith, is a passageway or conduit 9, with the outer end of each of which a branch pipe 40 10 communicates, the latter leading to exhaust heaters (not shown) of an automobile.

A valve 11 is provided in each of the casings 8 to direct the passages of exhaust gases either to the mufflers or branch pipes 10. As shown 45 in Figure 2, these valves are fixed to rock shafts 12 journaled in the casings 8, and the inner ends thereof project outwardly beyond the inner ends of the passageways 9. To provide for the simultaneous actuation of the 50 valves 11, I employ a valve actuating mecha-

nism comprising a depending bracket 15 attached to the underface of the automobile flooring 16 by bolts 17 at a point centrally of the exhaust pipes 5 and 6. A bell-crank lever 18 is pivoted to the bracket 15 as at 19. 60 A longitudinally movable actuating rod 20 has its forward end pivotally connected to the lower end of the bell-crank lever 18 as at 21, while its opposite end carries a yoke or clevis 22. A transverse equalizer bar 23 extends horizontally through the yoke or clevis and is supported therein for pivotal movement about a vertical pin 24 passing through the clevis or yoke. Normally parallel arms or levers 25 are fixed to the projecting ends 70 of the rock shafts 12 and have their upper ends pivotally engaging the extremities of the equalizer bar 23.

Countersunk in a recess 26 in the automobile flooring 16 in vertical alinement with the lateral leg of the bell-crank lever 18, is a socket 27, having a central opening 28 in its bottom. A vertically arranged adjusting screw 29 passes through the opening 28 and is formed with an annular shoulder 30 resting upon the bottom of the socket 27 to retain the screw 29 against movement in a downward direction. A stop washer 32 is received on the screw slightly below the socket and serves to retain the former against upward 80 movement, the stop washer being held in position by lock nuts 33 engaged with the screw.

As shown in Figure 4, the lateral leg of the bell-crank lever 18 is formed with a pair of parallel ears 34 in which a cylindrical member 35 is journaled. This member 35 is formed with an interiorly threaded vertical bore 37 through which the bolt 29 passes and engages. A rectangular head 39 is formed on the upper end of the screw 29 and is adapted to be engaged by a detachable crank handle 40 when it is desired to rotate the bolt and hence actuate the valves 11.

To prevent dirt and other foreign matter from entering the socket 27, a pivoted closure 42 for closing the socket is provided. This closure 42 is normally received in a countersink 43 in an upper edge of the socket, and has one end pivotally engaged with a vertical bolt 44 passing through the flooring 16. An 100 expandable spring 45 encircles this bolt and engages a nut 46 thereon to draw the bolt downwardly and thereby hold the closure within the countersink 43. A recess 48 is formed in one side of the socket to permit the 105

55 valves 11, I employ a valve actuating mechanism comprising a depending bracket 15 attached to the underface of the automobile flooring 16 by bolts 17 at a point centrally of the exhaust pipes 5 and 6. A bell-crank lever 18 is pivoted to the bracket 15 as at 19. 60 A longitudinally movable actuating rod 20 has its forward end pivotally connected to the lower end of the bell-crank lever 18 as at 21, while its opposite end carries a yoke or clevis 22. A transverse equalizer bar 23 extends horizontally through the yoke or clevis and is supported therein for pivotal movement about a vertical pin 24 passing through the clevis or yoke. Normally parallel arms or levers 25 are fixed to the projecting ends 70 of the rock shafts 12 and have their upper ends pivotally engaging the extremities of the equalizer bar 23.

entrance of a sharp prying implement such as the element 49 cast with the crank handle 40 to raise the closure 42 from the countersink and permit it to be rotated to expose the head 39 of screw 29.

Contractile springs 50 are engaged with the lower ends of the arms or levers 25 and are anchored as at 51 to the casings 8. A contractile spring 52 is attached to the lower end 10 of the bell-crank lever 18 and is anchored as at 53 to part of the automobile. Due to the arrangement of the springs 50 and 52, tension is exerted in opposite directions, whereby 15 the movable parts, particularly the valves 12, are at all times held stationary and free from vibration. Not only is vibration eliminated when the valves are open or closed, but also when the valves are in partly open position.

When it is desired to actuate the valves to a 20 position to establish communication between the exhaust pipes and their mufflers and sever communication between the exhaust pipes and branch pipes 10, the screw is rotated by means of the crank handle 40, to rock the bell-crank lever 18, operating the rod 20 to the dotted line position. When it is desired to establish communication between the exhaust pipes and branch pipes 10, the valves 25 are actuated to the position shown in Figure 30 1 by rotating the screw in the reverse direction. It will be observed that the valve can be adjusted to a partly open position by rotating the screw to dispose the valves at a predetermined point. As heretofore mentioned, the levers 25 secured to the rock shafts 12 have their opposite ends pivotally connected to the equalizer bar 23. This construction has been adopted for the purpose of providing a certain amount of relative 35 movement between the rock shafts 12 to compensate for differences in tension of the springs 50 whereby the valves 11 will be each forced to fully closed or open position, and it will be apparent that if the lever 18 is actuated to place the valves 11 in fully open position as shown in Figure 1, and the tension of the springs 50 is not equal, one of the valves will reach fully open position in advance of its companion valve. The equalizer bar will 40 have assumed an angular position. Further actuation of the lever will cause the other valve to assume fully open position because of the equalizer bar 23. The same operation 45 will occur to seat the valves in fully closed 50 position, as will be obvious.

What is claimed is:

1. In a valve actuating mechanism, a plurality of pivotally supported valves movable in unison to open or closed position, means 60 connecting said valves, a lever pivoted intermediate its ends and having operative engagement with the connecting means, and a manually operable threaded element engaging the lever to adjust the latter about its pivot and thereby simultaneously actuate the valves.

2. In a valve actuating mechanism, a plurality of pivoted valves movable in the same plane and operatively connected together for simultaneous adjustment, a lever pivotally supported intermediate its ends, an operating 70 rod pivotally connected with the lever and having operative engagement with the valves, a member loosely carried by one end of the lever and having a threaded bore, and an adjusting screw supported adjacent the lever 75 and having operative engagement with the threaded bore whereby upon rotation of the screw, the lever will be rocked on its pivot to correspondingly adjust the valves.

3. In a valve actuating mechanism, a plurality of pivotally supported valves, a manually operable shiftable lever, and a pivotally supported bar movable with the lever and having its ends pivotally connected to the valves for operating the latter.

4. In a valve actuating mechanism, a plurality of pivoted valves movable in parallelism, parallel arms fixed to the valves, an actuating rod, an equalizer bar pivotally carried by the actuating rod and having its ends 90 pivotally connected with the arms, and manually operable means for moving the actuating rod in a longitudinal direction to rock the arms and thereby adjust the valves.

5. In a valve actuating mechanism, a plurality of pivoted valves movable in parallelism, parallel arms fixed to the valves, an actuating rod, an equalizer bar pivotally carried by the actuating rod and having its ends pivotally connected with the arms, manually operable means for moving the actuating rod in a longitudinal direction to rock the arms and thereby adjust the valves, and counter-balancing springs connected with the arms and actuating rod for retaining the movable 105 parts against vibration.

6. In a valve actuating mechanism, a plurality of pivotally supported valves, parallel arms fixed to the valves, a longitudinally movable valve actuating rod, an equalizer bar 110 pivotally carried by the valve actuating rod and having its ends pivotally engaged with the arms, a manually operable lever connected with the actuating rod, and counter-balancing springs connected with the arms and lever 115 respectively to normally retain the movable parts against vibration.

7. In combination, a pair of valve assemblies each having a valve therein, an operating lever for each valve, a common controller 120 for operating both valves, means for adjusting the position of the controller to position said valves, and oppositely acting resilient means connected to the operating levers and adjusting means respectively for resiliently 125 retaining the valves and adjusting means in predetermined position.

8. In combination, a pair of valve assemblies each having a valve therein, an operating lever for each assembly, resilient means 130

connected to each lever for normally urging the valves to seated position, a common controller for said valves, adjusting means operative through the controller for positioning 5 said valves against the tension of the resilient means, and a second resilient means connected to said adjusting means and functioning in opposition to the first named resilient means to balance the tension exerted by the latter 10 whereby to resiliently mount the valves and the operating mechanism therefor.

9. In combination, a plurality of valves, resilient means for each valve for normally urging the latter to closed position, an actuating lever, a bar pivotally connecting said 15 valves and pivotally secured to the actuating lever, and resilient means connected to the actuating lever and acting upon the latter to normally urge the valves to open position.

In witness whereof I have hereunto set my 20 hand.

FRANK A. WHITTEN.
